UNITED STATES PATENT OFFICE.

WALTER F. KRAHE, OF BROOKLYN, NEW YORK.

AMUSEMENT APPARATUS.

1,421,960.

Specification of Letters Patent.

Patented July 4, 1922.

Application filed February 10, 1921. Serial No. 443,798.

To all whom it may concern:

Be it known that I, WALTER F. KRAHE, a citizen of the United States, and residing at Brooklyn, in the county of Kings and State of New York, have invented certain new and useful Improvements in Amusement Apparatus, of which the following is a specification, such as will enable those skilled in the art to which it appertains to make and 10 use the same.

This invention relates to amusement apparatus adapted for use at amusement places of various kinds and classes, and the object of the invention is to provide an apparatus of the class specified which is designed to amuse both old and young and which may be mounted or set up wherever such apparatus are required; a further object being to provide an apparatus of the 15 class described which involves a plurality of spaced disks rotatably mounted in connection with a suitable platform and passenger carrying members or cars adapted to be moved over said platform and disk by the 20 operation or rotation of said disks, and with this and other objects in view the invention consists in an apparatus of the class and for the purpose specified which is simple in construction and operation, and efficient in use, 25 and which is constructed and operated as hereinafter described and claimed.

The invention is fully disclosed in the following specification, of which the accompanying drawing forms a part, in which the 30 separate parts of my improvement are designated by suitable reference characters in each of the views, and in which:—

Fig. 1 is a plan view of one form of my apparatus;

Fig. 2 a bottom plan view thereof with part of the construction omitted;

Fig. 3 a central and longitudinal section through the apparatus and showing certain parts of the construction which I employ 45 and which are not shown in Figs. 1 and 2;

Fig. 4 a side and sectional detail view of a passenger carrying member or car, one or more of which I employ, and three of which are shown in Fig. 1 of the drawing;

Fig. 5 a view similar to Fig. 1 but showing a modified form of apparatus, with part of the construction broken away and in section;

Fig. 6 a bottom plan view of the construction shown in Fig. 5 with a detail of 55 the construction omitted;

Fig. 7 a partial central longitudinal section through the apparatus shown in Figs. 5 and 6 and showing a detail of construction which is not shown in Figs. 5 and 6; 60

Fig. 8 a partial section on the line 8—8 of Fig. 6;

Fig. 9 a view similar to Fig. 1 and showing a modification; and,

Fig. 10 a longitudinal central section of 65 the apparatus shown in Fig. 9.

In Figs. 1 to 3 inclusive, I have shown one form of my improved amusement apparatus in which I employ a suitable elongated framework 10, the top portion 11 of which 70 constitutes the platform of the apparatus, and said platform is supported by a plurality of leg members 12 and is reinforced by angularly arranged rib members 13 which join centrally as shown at 14. The platform 11 is provided with an upstanding bumper wall 15 which is approximately elliptical in form, or comprises parallel side members 16 joined by arc-shaped end members 17, and the side members 16 of the 80 bumper wall are provided with spaced inwardly directed arc-shaped projections 18, two of which are employed on each wall, in the form of construction shown.

The platform 11 is provided, in the form 85 of construction shown, with three large apertures 19 in which a corresponding number of disks 20 are adapted to fit and rotate, it being understood that the upper faces of the disks 20 are in approximately the same 90 horizontal plane as the upper face of the platform 11.

A shaft 21 is mounted longitudinally of the apparatus and beneath the disks 20, said shaft passing through the central portions 95 14 of the rib members 13 and also through transverse rib members 22 on said frame which form the bearings or supports for said shaft. Secured to said shaft are three drive wheels 23 adapted to engage the lower 100 face of the disks 20 to rotate said disks by the frictional engagement therewith, and three other wheels 24 are mounted to freely rotate upon the shaft 21. I also provide suitable brackets 25 secured to the opposite 105 sides of the framework 10 in the manner

shown in Fig. 2 of the drawing and in which wheels 26 are rotatably mounted, said wheels as well as the wheels 24 forming a support for the separate disks 20 and permit of the 5 free rotation or operation of said disks when driven by the friction wheels 23.

Secured to the shaft 21 is a gear 27 in connection with which a gear 28, on the shaft of an electric motor 29, operates where-
10 by the shaft 21 may be rotated. Mounted upon the central portions 14 of the rib members 13 of the framework are upstand-
15 ing pins 30 which pass centrally through the disks 20 and upwardly into a central partitioning and bumper wall 31, as clearly shown in Figs. 1 and 3 of the drawing, said wall extending centrally and longitudinally of the apparatus and the ends thereof terminate approximately, centrally of the end
20 disks 20 of the apparatus, as clearly shown in Fig. 1 of the drawing.

I also employ in connection with the apparatus a number of passenger carrying members or cars 32, three of which are
25 shown in Fig. 1 of the drawing, and one of which is shown in detail in Fig. 4 of the drawing, and said cars, in the form of construction shown, are circular or thimble-shaped in form and consist of an upwardly
30 cylindrical wall 33 having a closed bottom 34 in which is mounted a plurality of dual roller casters 35. Secured to the lower end of the upstanding wall 33 is an annular bumper ring 36 which is adapted to operate
35 in connection with the walls 15, 16, 17, 18 and 31 of the apparatus to guide the separate cars in their movement over the platform 11 and the separate disks 20 thereof. An annular seat member 37 is mounted within the
40 upstanding wall 33 and secured in position by a suitable bracket 38, and when the apparatus is in use a number of people sit upon the annular seat 37 in the separate cars 32 and as the disks 20 are put into operation.
45 said disks being all rotated in the direction of the arrow α of Fig. 1, said cars will be advanced over the platform and over said disks from right to left, and from left to right, or in the direction in which the disks
50 20 are rotated, it being understood that it is the operation or rotation of the disks 20 that advances the separate cars 32 over the platform or conveys said cars from one disk to the other.

55 In the construction shown in Figs. 5 to 8 inclusive the framework 10 is of the same general form as that shown in Figs. 1 to 3 inclusive, except that the inwardly directed arc-shaped members 18 on the side bumper
60 walls 16 are eliminated and, in this form of construction, the wheels 23, 24 and 26 as well as the shaft 21 are also eliminated, and the disks 20 are provided with large gears or gear facings 39 and two smaller gears 40 are
65 mounted centrally of the intermediate trans-

verse members 22 of the framework 10, and each of which cooperates with the gears 39 of the central and one of the side disks 20, as clearly shown in Figs. 5 and 7 of the drawing.

70

The disks 20 are provided below the gears 39 with annular beveled faces 41 and four angularly arranged wheels 42 are supported upon the rib members 13 and operate in connection with the bevel faces 41 of each 75 of said disks, as clearly illustrated in Figs. 6 and 8 of the drawing, and said wheels serve to support the disks 20 in proper position, and also prevent lateral movement of the disks in the operation of the apparatus, as 80 will be apparent on a consideration of Fig. 8 of the drawing.

The gears 40 are mounted upon shafts 43 which extend downwardly through the transverse members 22 and secured to the 85 lower ends of said shafts are beveled gears 44 in connection with which other beveled gears 45 secured to a shaft 46 operate. The shaft 46 is mounted in bearings 47, 48 and 49 secured to or formed integral with the 90 framework of the apparatus, or the transverse members 22 thereof as well as the central portion 14 of the rib members 13 located below the central disk 20. A gear 50 is secured to the shaft 46 and another gear 51 95 on the shaft of an electric motor 52 operates in connection with the gear 50 to drive the shaft 46 and thus rotate the gears 40 through the beveled gears 44—45, and the rotation of the gears 40 will rotate all of the disks 20 100 in the direction of the arrow α^2 of Fig. 5.

Mounted upon the central portion 14 of the rib members 13 are upstanding pins 53 which pass centrally through the disks 20 and upwardly into the central partitioning 105 and bumper wall 31 in the same manner as the pins 30, and these pins 53 as well as the pins 30 serve to aid in supporting the wall 31 in both forms of construction shown, said walls being also supported upon the 110 platform 11 between the central and end disks.

It will be apparent from the foregoing that in the construction shown in Figs. 1 to 3 inclusive, the disks 20 are frictionally driven while in the construction shown in Figs. 5 to 8 inclusive, the disks 20 are driven positively through the gearing hereinbefore described, and said disks are supported and rotate upon the angularly arranged wheels 120 42 which cooperate with the beveled faces 41 of said disks. I also preferably employ, in the construction shown in Figs. 5 to 8 inclusive, supplemental frictionally driven disks 54, which are mounted to rotate in 125 apertures 55 in the platform 11, and said disks are located at the opposite sides of the platform and between the central and end disks 20, as clearly shown in Fig. 5 of the drawing, and the periphery of the small 130

disks 54 operate in connection with the periphery of the disks 20, and by means of which said disks 54 are rotated in the rotation of the disks 20. The disks 54 are mounted on shafts 56 which pass downwardly into the transverse members 22, as clearly shown in Fig. 6 of the drawing.

The object of providing the small disks 54 is to prevent the stalling of the cars or 10 passenger carrying members 32 and between the separate disks 20, in other words, the disks 54 serve to carry or convey such cars from one disk to the other.

The construction shown in Figs. 9 and 10 15 of the drawing is the same in all respects as that shown in Figs. 1 to 3 inclusive except that the central bumper wall 31 is omitted and substituted for the arc-shaped projections 18 are inwardly projecting members 57 which are approximately triangular in form and the inner ends of which are rounded as shown at 58.

Another difference in the construction 25 consists in substituting the pins 59 for the pins 30 in the construction shown in Figs. 1 to 3 inclusive, the pins 59 being preferably provided with heads 60 which aid in holding the disks 20 in proper position.

In this construction the end disks 20 are 30 rotated by the wheels 23 as in Figs. 1 to 3 inclusive, while the central disk 20 is rotated in an opposite direction to said end disks by changing the position of the wheels 23-24, in other words, the central disk 20 is rotated 35 by a friction wheel located at the left instead of at the right of said disk as viewed in the drawings, and the end disks 20, in this construction, are rotated by friction wheels located at the right of said disks.

40 As above stated with the exception of the changes in construction, above set out, the general construction of the apparatus shown in Figs. 9 and 10 will be the same as that shown in Figs. 1 to 3 inclusive, but by eliminating the central bumper wall 31 and rotating the central disk in the opposite direction to the rotation of the end disks, the passenger carrying members or cars 32 will travel over the platform and said disks in the direction of the arrowed line α^3 shown in Fig. 1 of the drawing, the inwardly projecting members 57 serving to guide the members or cars 32 in this operation.

It will be understood that the disks in the 55 construction shown in Figs. 9 and 10 may be operated in any desired manner, and while I have shown a platform of specific construction and a specific arrangement of disks thereon, my invention is not necessarily limited in this respect nor am I limited to any specific arrangement of bumper wall on said platform and which serve to guide the passenger carrying member or cars over the apparatus, and various changes in and modifications of the construction herein shown

and described may be made, within the scope of the appended claims, without departing from the spirit of my invention or sacrificing its advantages.

Having fully described my invention, 70 what I claim as new and desire to secure by Letters Patent, is:—

1. An apparatus of the class described comprising an elongated platform, a plurality of disks mounted in and spaced longitudinally of said platform, carriage members mounted on and movable over said platform and disks, a drive shaft mounted longitudinally of and beneath said platform, and means for gearing said shaft with said disks 75 whereby said disks may be rotated in predetermined directions to move said members over said platform and from one disk to another.

2. An apparatus of the class described 80 comprising an elongated platform, a plurality of disks mounted in and spaced longitudinally of said platform, carriage members mounted on and movable over said platform and disks, a drive shaft mounted longitudinally of and beneath said platform, means for gearing said shaft with said disks whereby said disks may be rotated in predetermined directions to move said members over said platform and from one disk to 90 another, and bumper walls for guiding said members in their movement.

3. An amusement apparatus of the class described comprising a suitable platform, a plurality of disks spaced therein and the 100 axis of which are arranged in an approximately common line, carriage members mounted on and movable over said platform and disks, means for rotating said disks to move said members over said platform and 105 from one disk to another, and bumper walls for guiding said members in their movement.

4. An amusement apparatus of the class described comprising a suitable platform, a plurality of disks spaced therein and the 110 axis of which are arranged in an approximately common line, carriage members mounted on and movable over said platform and disks, means for rotating said disks to move said members over said platform and 115 from one disk to another, bumper walls for guiding said members in their movement, and other bumper elements cooperating with said bumper walls for guiding the movement of said members.

5. An apparatus of the class described 120 comprising an elongated platform having semi-circular end portions, disks mounted in the end portions of said platform, another disk mounted in said platform intermediate 125 of said first named disks, carriage members mounted on and movable over said platform and disks, and means for rotating all of said disks to move said members over said platform and from one disk to another.

6. An apparatus of the class described comprising an elongated platform having semi-circular end portions, disks mounted in the end portions of said platform, another 5 disk mounted in said platform intermediate of said first named disks, carriage members mounted on and movable over said platform and disks, means for rotating all of said disks to move said members over said platform and from one disk to another, and 10 means for controlling the course of said members.

7. An apparatus of the class described comprising an elongated platform having 15 semi-circular end portions, disks mounted in the end portions of said platform, another disk mounted in said platform intermediate

of said first named disks, carriage members mounted on and movable over said platform and disks, means for rotating all of said 20 disks to move said members over said platform and from one disk to another, means for controlling the course of said members, and bumper walls for guiding said members in their movement. 25

In testimony that I claim the foregoing as my invention I have signed my name in presence of the subscribing witnesses this 9th day of February, 1921.

WALTER F. KRAHE.
